UNITED STATES PATENT OFFICE.

CHARLES H. HAWKINS, OF LONG ISLAND CITY, NEW YORK.

MACHINE FOR INSULATING ELECTRIC CONDUCTORS.

SPECIFICATION forming part of Letters Patent No. 783,197, dated February 21, 1905.

Application filed August 2, 1904. Serial No. 219,220.

To all whom it may concern:

Be it known that I, CHARLES H. HAWKINS, a citizen of the United States, residing at Long Island City, in the county of Queens and State 5 of New York, have invented certain new and useful Improvements in Machines for Insulating Electric Conductors, of which the following is a specification, such as will enable those skilled in the art to which it appertains to 10 make and use the same.

This invention relates to apparatus for insulating wires used for electric conductors; and the object thereof is to provide an apparatus of this class by means of which a conductor wire or wires may be provided with 15 two coatings or coverings of insulating material; and with this and other objects in view the invention consists in an improved machine of the class specified and in a supplemental 20 machine member or device forming a part thereof, constructed as hereinafter described and claimed.

The invention is fully disclosed in the following specification, of which the accompanying 25 drawings form a part, in which the separate parts of my improvement are designated by suitable reference characters in each of the views, and in which—

Figure 1 is a side view of my improved wire 30 coating or covering machine; Fig. 2, a back side view of one of the parts thereof, part of the construction being shown in section; Fig. 3, a view of that part of the machine shown in Fig. 2 and looking in the direction of the 35 arrow x , part of the construction being also in section; and Fig. 4, a sectional view, on an enlarged scale, of part of the construction shown in Fig. 2 and in the same position.

In the drawings forming part of this specification, reference being made to Fig. 1, I 40 have shown at a and a^2 two wire coating or covering machines known as the "Royle," and these machines in ordinary use are intended for giving a wire or electric conductor a single coating or covering of insulating material, 45 such as rubber. Each of these machines is provided with a head b , and the head b is provided at the top thereof with pipes b^2 , by means of which liquid rubber or similar material is fed into the heads b . In practice these

machines have heretofore been used separately, and in this operation the wire c was drawn through the head b and the rubber in a liquid or plastic condition was fed through or forced through said head and out through 55 a collar or bushing d , having slots formed therein, through which the rubber emerged in the form of strips d^2 , and suitable means were provided for pressing the rubber strips onto the wire c and securing the same thereto, 60 so as to form a complete cover or insulation therefor. In my improvement, as hereinbefore stated, I employ two of the Royle machines, and the collar or bushing d in the second machine a^2 is made larger, so that the wire 65 c after it has received one coat will pass therethrough, and the rubber or other material in a liquid or plastic condition is forced through the head b of the second machine a^2 in the same manner as with the first machine a . 70

The chief feature of my invention consists of a separate supplemental machine or device e , two of which are shown in Fig. 1 and each of which is exactly the same in construction and one of which is placed between the Royle 75 machines a and a^2 and the other at the left of the machine a^2 , as shown in Fig. 1, and the object of these supplemental machines or devices is to facilitate or accomplish the result of providing the wire or conductor with two 80 coatings or coverings of insulating material and also to facilitate the feeding of said wire or conductor through the apparatus comprising the separate parts a and a^2 and the additions thereof consisting of said supplemental 85 parts e .

Each of the supplemental machines or devices e comprises a hollow upright member or standard e^2 , at the top of which is a yoke-shaped head e^3 , in which are mounted two 90 shafts e^4 , geared together, as shown at e^5 , and these shafts project at one side of the head e^3 and are provided with grooved wheels e^6 , between which the wire c passes, and one end of the top shaft e^4 is mounted in a vertically- 95 movable block e^7 in one side of the head e^3 , and in the opposite side of said head is a vertically-movable set-screw e^8 , which operates on a bearing-block e^9 , which rests on the opposite end of said top shaft or the end thereof with which 100

one of the wheels e^1 is connected, and by means of this construction the wheel e^6 on the top shaft e^4 may be given a slight vertical movement.

5 The end of the bottom shaft e^4 opposite the wheel e^6 thereon is provided with a worm-gear f , and at the left-hand side of the upright or standard e^2 is mounted a shaft f^2 , provided with a worm f^3 , which operates in connection with the worm-gear f . The shaft f^2 is mounted in a vertical plane and at a backwardly-inclined angle, and the upper end of this shaft is provided with bearings f^4 , secured to the head e^3 , and the lower end thereof is 10 provided with a bearing f^5 , connected with a standard f^6 , secured to the base of the upright or standard e^2 , and mounted on the shaft f^2 is a sleeve f^7 , to the lower end of which is secured a friction gear-wheel g , and the sleeve 15 f^7 is movable longitudinally of the shaft f^2 , and the friction gear-wheel g operates in connection with a friction gear-wheel g^2 , secured to a shaft g^3 , which passes longitudinally through the base of the upright or standard 20 e^2 . The shaft g^3 passes through a bearing g^4 , in which it is movable longitudinally, and secured to said shaft is a collar g^5 , between which and the bearing g^4 is a spring g^6 , which normally serves to force the shaft g^3 and the wheel 25 g^2 in the direction of the wheel g , and the end of said shaft g^3 opposite the wheel g^2 is provided with a fixed pulley g^7 and a loose pulley g^8 .

30 Mounted above the end of the shaft g^3 on which the pulleys g^7 and g^8 are placed is a rod h , which is parallel with the shaft g^3 and movable longitudinally thereon and one end of which projects into the upright or standard e^2 , and said rod is provided centrally with a support or bearing h^2 , connected with the support or bearing of the shaft g^3 and secured to the rod h between the support or bearing h^2 thereof and the upright or standard e^2 , and adjacent to said support or bearing is an arm h^3 , through 35 which is passed a guide-pin h^4 , secured to the support or bearing h^2 , and between the arm h^3 and the upright or standard e^2 is a spring h^5 , which operates to force the rod h outwardly or backwardly, and said rod is provided at its 40 outer or rear end with two belt-shifting fingers h^6 , which normally rest adjacent to the loose pulley g^8 .

45 In the bottom of the upright or standard e^2 is a short shaft i , provided with an arm i^2 , through or adjacent to which the inner or front end of the rod h passes, and said rod is provided with a pin i^3 , in connection with which the arm i^2 operates to force the rod h inwardly or forwardly. The shaft i is also provided 50 with a pedal-arm i^4 , which projects forwardly and which is provided with a foot-piece or pedal i^5 , adjacent to which is pivoted a dog i^6 , which normally rests in the position shown in Fig. 2 and which is provided with a nose i^7 , 55 which holds the pedal-arm i^4 in a depressed

position, and it will be understood that the parts h , i , i^2 , and i^4 constitute a belt-shifting device by means of which a power-belt may be shifted from one of the pulleys g^7 or g^8 to the other whenever desired, and the object of 70 the arm h^3 , which is secured to the rod h , and the guide-pin h^4 is to prevent the turning of the rod h . In the position of the parts shown in Fig. 3 the power-belt will be on the loose pulley g^8 , and when it is desired to shift said 75 belt onto the fixed pulley g^7 the pedal-arm i^4 is depressed and locked in the depressed position by the dog i^6 , and the parts remain in this position as long as the machine is in operation, and the belt can be shifted to the loose pulley 80 g^8 by simply releasing the dog i^6 from the pedal-arm i^4 .

85 The upper end of the sleeve f^7 is provided with two collars j , held in place by set-screws j^2 , and between these collars is placed a supplemental sleeve k , provided at one side with a rack-bar k^2 , and passing through the upright or standard e^2 is a shaft k^3 , provided with a gear-wheel k^4 , which operates in connection with the rack-bar and at the opposite sides of 90 which are flanges or rims k^5 , between which the rack-bar k^2 fits and moves and which serve to prevent the supplemental sleeve k from turning on the sleeve f^7 , and the shaft k^3 is provided at its opposite end with a worm-gear k^6 , 95 and below the worm-gear k^6 is a shaft m at right angles to the shaft k^3 and provided with a worm m^2 , which operates in connection with the worm-gear k^6 , and the shaft m is provided with a handle or wheel m^3 , by which it may be turned.

100 It will be understood that the shaft f^2 is turned by the wheel g^2 operating in connection with the wheel g , and by means of the shaft k^3 and the gearing in connection therewith and the rack-bar k^2 the sleeve f^7 on the shaft f^2 , with which the wheel g is connected, may be moved longitudinally of the shaft f^2 , and this operation will bring the wheel g nearer to or farther from the center of the wheel g^2 , according to 105 the direction in which the sleeve f^7 is moving, and by means of this construction the speed of the shafts e^4 of the head e^3 , and with which the grooved wheels e^6 are connected, may be regulated or increased or decreased as desired. 110

115 In the apparatus shown in Fig. 1 one of the supplemental machines or devices e is placed between the Royle machines a and a^2 and the other at the left of the Royle machine a^2 , and by means of this construction the wire c , as hereinbefore stated, may be provided with two coatings or coverings of insulating material, the first coat or covering being shown at c^2 and the second at c^3 . It will also be understood that this operation is continuous, the separate parts of the apparatus being placed in line and the wire c being continually passed therethrough. The grooved wheels e^6 on the supplemental machine or device e at the left of the Royle machine a^2 may be larger than 120 125 130

those on the other supplemental machine or device *e*, so as to adapt the same to the application of the second coating or covering to the wire *c*.

5 From the construction herein shown and described it will be seen that my improvement consists in the supplemental machine or device *e*, two of which are employed in the apparatus shown in Fig. 1, and in the combination therewith of the Royle machines as shown in Fig. 1 and as herein described.

Having fully described my invention, what I claim as new, and desire to secure by Letters Patent, is—

15 1. In an apparatus of the class described, a supplemental machine member, comprising a main upright or standard, two shafts mounted in the top thereof and geared in connection and provided at one end with interoperating grooved wheels, one of said shafts being also provided at the other end with a worm-gear, an upright shaft mounted adjacent to the main upright or standard and provided with a worm operating in connection with said worm-gear, 25 and means for varying the speed of the upright shaft, substantially as shown and described.

2. In an apparatus of the class described, a supplemental machine member, comprising a main upright or standard, two shafts mounted in the top thereof and geared in connection and provided at one end with interoperating grooved wheels, one of said shafts being provided at the opposite end with a worm-gear, 35 an upright shaft mounted adjacent to the main upright or standard and provided with a worm operating in connection with the worm-gear, a sleeve movable longitudinally on said upright shaft and provided at its lower end with 40 a friction-gear, another shaft mounted hori-

zontally in the main upright or standard and provided at one end with a friction-gear which operates in connection with that on said sleeve, and means for moving said sleeve longitudinally on the upright shaft, substantially as 45 shown and described.

3. In an apparatus of the class described, a supplemental machine member, comprising a main upright or standard, two shafts mounted in the top thereof and geared in connection 50 and provided at one end with interoperating grooved wheels, a worm-gear connected with the other end of one of said shafts, an upright shaft mounted adjacent to the main upright or standard and provided with a worm operating in connection with the said worm-gear, a main sleeve mounted on the upright shaft and movable longitudinally thereof and provided at its lower end with a friction-gear, a shaft horizontally mounted in the bottom of 55 the main upright or standard and provided with a friction-gear operating in connection with that on said sleeve, and means for moving said sleeve longitudinally of the upright shaft comprising a supplemental sleeve mounted on the upper end of the main sleeve and provided with a rack-bar, a horizontal shaft mounted in the main upright or standard and provided with a gear-wheel which operates in connection with said rack-bar, and means for 60 turning said last-named shaft, substantially as shown and described.

In testimony that I claim the foregoing as my invention I have signed my name, in presence of the subscribing witnesses, this 1st day 75 of August, 1904.

CHARLES H. HAWKINS.
